UNITED STATES PATENT OFFICE.

FRANK A. WEEKS, OF PLAINFIELD, NEW JERSEY.

INKSTAND.

1,176,800.

Specification of Letters Patent. Patented Mar. 28, 1916.

Application filed July 3, 1914. Serial No. 848,744.

To all whom it may concern:

Be it known that I, FRANK A. WEEKS, a citizen of the United States, and a resident of Plainfield, in the county of Union and State of New Jersey, have invented certain new and useful Improvements in Inkstands, of which the following is a specification.

The invention relates to improvements in inkstands of the class comprising a glass base in which a well is provided for ink and having a reduced forward portion to be utilized as a dip chamber for the pen, and a removable cover placed on top of the glass base and covering the well and also at the proper time the dip chamber.

The inkstand in the main comprises two parts, one being the glass base and the other the removable cover, and the cover is in two sections which by being connected together constitutes in effect a single piece. One section of the cover remains stationary on the inkstand while the other section of the cover is in the form of a slide which may be pushed inwardly under the main body of the cover to expose the dip chamber for use and thereafter drawn outwardly to cover said dip chamber when the inkstand is not in use.

The main individual features of novelty connected with the present invention reside in the cover portion of the inkstand, this cover being a stationary cover having the sliding section for closing and opening, according to its position, the dip chamber connected with the ink-well in the base.

The invention will be fully understood from the detailed description hereinafter presented, reference being had to the accompanying drawings, in which:

Figure 1 is a top view of an inkstand embodying my invention, the ink-well and dip chamber being closed by the cover; Fig. 2 is a corresponding view of the glass base of the inkstand, the cover having been omitted; Fig. 3 is a vertical section through the inkstand and cover taken on the dotted line 3—3 of Fig. 1; Fig. 4 is a transverse section through the inkstand taken on the dotted line 4—4 of Fig. 1; Fig. 5 is a detached bottom view of the cover of the inkstand, this figure showing the sliding section of the cover as moved inwardly to the position it occupies when the dip-chamber in the base is uncovered; Fig. 6 is a top view of a modified construction of the inkstand, the modification residing principally

in making the body of the cover rectangular instead of circular and in making the ribs which retain the cover on the inkstand straight instead of segmental; Fig. 7 is a top view of the glass base shown in Fig. 6, the cover being omitted; Fig. 8 is a vertical section through the inkstand and cover shown in Fig. 6, and Fig. 9 is a detached bottom view of the cover shown in Figs. 6 and 8.

In the drawings 10 designates the glass base and 11 the cover therefor, the base preferably being an integral block of glass containing an inkwell 12 having a forwardly projecting portion or dip chamber 13 in communication with said well. The base 10 is formed on opposite sides of the upper edge of the main body of the well 12 with upwardly extending arc flanges 14 whose front ends terminate at the sides of the forwardly projecting dip chamber 13, while the rear ends of said flanges 14 end at opposite sides of the center of the rear portion of the well 12 and form stops for the cover 11 to aid in preventing rotary movement of said cover.

The forwardly projecting well portion or dip chamber 13 affords a commodious opening to receive the pen and enable the latter to receive a suitable supply of ink, and in order to prevent the pen from being moved unduly inwardly into the well, I provide the latter with an integral vertical standard 15 which rises from the floor of the well and is set inwardly from the dip chamber 13. The standard 15 is centrally in line with the length of the dip chamber 13 and the outer vertical edges of said standard are separated from the adjacent vertical walls of the well 12, and hence the ink from the well may pass freely around said standard and enter the dip chamber 13. The standard 15 at its upper end is below the upper edges of the flanges 14 and therefore in no danger of being broken during the use of the stand or during its shipment. When a pen is dipped into the dip chamber 13 and slides forwardly on the bottom thereof, as is frequently the case, the point of the pen will become arrested by the face of the standard 15 which has a vertical concave recess to aid in arresting the pen on any sliding movement thereof when dipped into the dip chamber 13. In the absence of some provision for preventing the pen when carelessly dipped into the dip chamber from sliding

a considerable distance into the well 12, the pen might so slide and strike the cover 11, thereby throwing the same from the base 10. I do not, however, limit my invention 5 to the standard 15 as the specific means for preventing the sliding movement of the pen from the dip chamber 13 into the well 12, since the same result may be obtained if the dip chamber 13 is considerably narrowed at 10 its inner end.

The cover 11 constitutes the main individual feature of the invention, and this cover comprises a body portion 16 and a 15 slideable section 17 connected therewith. The cover 11 will preferably be formed of rubber or composition and will have a downwardly extending flange 18 to rest upon the top of the base 10 and engage the flanges 14 thereon, as shown more clearly in Fig. 4. The flange 18 by its engagement with the flanges 14 prevents the cover from being slid laterally from off the base 10. The cover 11 at its rear edge is formed, on the flange 18, with an inwardly projecting thickened 20 section 19, shown more clearly in Fig. 5, which is adapted to fit in between the rear ends of the arc flanges 14 and prevent the cover from having any rotary movement on the base 10. The slideable section 17 of the cover 11 is slightly wider than the top 25 of the dip chamber 13, and it is adapted to have a movement outwardly, as shown in Figs. 1 and 3, to cover said dip chamber or inwardly to the position shown in Fig. 5 to 30 uncover said dip chamber for use. The slideable section 17 has a finger-piece 20 at its front end by which it may be operated, and the edge of the body section 16 of the cover 11 is recessed in line with the section 17 to 35 receive said finger-piece 20 when the section 17 is moved to its retracted position illustrated in Fig. 5. The section 17 of the cover is in the form of a flat strip provided with shoulders 21 along its opposite sides, and 40 said section is confined between depending lugs 22 which are integral with the body section 16 of the cover and extend outwardly from the lower face thereof and carry pins 23 whose ends are bent over below the shoul- 45 ders 21 and serve to support the section 17 from the bottom of said body section 16 and at the same time said bent pins 23 coöperate with the shoulders 21 in guiding the section 17 in its rearward and forward move- 50 ments. The body section 16 of the cover is also formed with a depending integral stud 24 which enters a guiding slot 25 in the top of the section 17, as shown in Figs. 3 and 4, and said pin and slot or recess, serve to aid 55 in guiding the section 17 and also afford at the ends of the slot or recess stops to arrest the section 17 at the extreme ends of its rearward and frontward movements.

When the cover 11 is placed on the base 60 10 its thickened section 19 will lie between

the rear ends of the flanges 14 and the width of the section 17 of the cover will lie between the front ends of said flanges 14, and in this condition of the parts the cover will be held against lateral displacement from the base 70 and be prevented from rotating and the section 17 will be held in line with the dip chamber 13, said section 17 covering said dip chamber 13 when drawn outwardly, as shown in Fig. 1, and exposing said chamber 75 when pushed inwardly to the position shown in Fig. 5.

In the modification of my invention shown in Figs. 5 to 8 inclusive, I number the glass base 30, and said base contains an 80 inkwell 31, forwardly extending dip chamber 32, and pen arresting standard 33, these parts corresponding exactly with the like parts shown in Figs. 1 to 4 inclusive. The base 30 is formed with two parallel flanges 85 34 extending from front to rear closely along the sides of the inkwell 31, and these two flanges 34 serve to receive the depending flanges 35 on the cover 36 which in this instance is rectangular in outline instead of 90 circular or of the form shown in Fig. 1. The cover 36 is provided with a body portion 37 and slideable section 38, the latter corresponding exactly with the slideable section 17 shown in Fig. 1. The rectangular cover 95 36 corresponds in all essential respects with the circular cover 16, and said cover 37 has at its lower side integral lugs 39 carrying pins 40 bent over upon side shoulders 41 of the slideable section 38 correspondingly 100 with the like features hereinbefore described with respect to Figs. 1 to 5 inclusive. I present Figs. 6 to 9 inclusive merely to indicate that with slight changes from the construction shown in Figs. 1 to 5 inclusive my 105 invention may be adapted for rectangular covers as well as circular covers.

My invention comprises an inkstand having the glass base section containing the well and dip chamber and proper flanges to hold 110 the cover, and a cover to rest upon the base and be capable of being elevated directly therefrom and having the slideable section to be drawn out from under the cover when the dip chamber is to be closed and pushed below 115 the cover when the dip chamber is to be opened.

What I claim as my invention and desire to secure by Letters-Patent, is:

1. An inkstand comprising an integral 120 glass base having an inkwell and a forwardly extending dip-chamber at one side in free communication with said well, and a cover adapted to rest freely on said base over said well and having and carrying an 125 independently slideable section to cover and uncover said chamber without exposing said well, said cover having a depending edge flange and said base flanges to receive said flange on said cover, for maintaining said 130

cover against lateral displacement without interfering with its elevation from said base, and said slideable section being a straight strip to be slid rearwardly under and frontwardly from under said cover, and said cover having on its bottom guiding and supporting means for said section.

2. An inkstand comprising a base having an inkwell and a forwardly extending dip-chamber communicating therewith, and a cover for said well having an independently slideable section to cover and uncover said chamber without exposing said well, said slideable section being a straight strip having shoulders along its sides and an elongated recess in its top and adapted to be moved rearwardly under and drawn forwardly from under said cover, and said cover having on its bottom guiding and supporting means for the sides of said strip and a depending pin within said recess.

3. An inkstand comprising a base having an inkwell and a forwardly extending dip-

chamber communicating therewith and formed with upwardly extending arc flanges at the sides of said well, said flanges being separated from each other at their rear ends and at their front ends terminating at the sides of said dip-chamber, and a cover for said well having a depending flange to engage said arc flanges and an independently slideable section to cover and uncover said dip-chamber without exposing said well, said section having its movement between the front ends of said arc flanges and said flange on the cover having a thickened part fitting between the rear ends of said arc flanges.

Signed at New York city, in the county of New York and State of New York, this 2nd day of July A. D. 1914.

FRANK A. WEEKS.
